APPARATUS FOR HANDLING AND COATING CONTAINERS

Wiltie I. Gladfelter, Philadelphia, Pa., and William A. Schmidt, Chase, Md., assignors to Crown Cork & Seal Company, Inc., Baltimore, Md., a corporation of New York

Application July 14, 1943, Serial No. 494,720

19 Claims. (Cl. 91—45)

The present invention relates to apparatus for coating the interiors of containers, such as beer cans, with liquid coating material such as heated wax compositions. The invention is concerned primarily with improved constructions in the coating machine and in the devices for handling a line of containers prior to, during and after the actual coating operation.

It is a primary object of the invention to simplify the article handling instrumentalities, and to eliminate a number of separate, independent handling or transferring operations heretofore employed with apparatus designed for the same general purpose.

In the coating of metallic containers with wax or the like, it has been the practice first to pre-heat the containers to a temperature approaching that of the liquid wax composition, to prevent chilling of the wax when it encounters the container walls, and to facilitate the distribution of the coating material thereon. Further, it has been the practice to drain the wax coating material from the interiors of the cans by conveying them, in inverted relation, through a drain oven, where the temperature of the containers and of the coating material is maintained sufficiently high to permit the excess material to flow from the containers, leaving a thin coating on the walls thereof. Finally, it has been the practice to distribute the coating material evenly upon the walls of the containers and more particularly to provide a slight excess of material along the line of junction between the container side walls and the bottom end members, around the double seam. This operation has been effected by conveying the containers in upright relation through a wax settling or distributing oven, where the temperature of the containers and the coating material is maintained sufficiently high to permit a slight amount of wax composition to settle along the line of junction between the side walls and the bottom.

The present invention aims to provide improved article handling and conveying devices in an organization of this general type.

Another object of the invention is to improve the construction and operation of the machine for coating the containers with wax, and to improve the container handling devices associated therewith.

A further object of the invention is to provide improved means for rendering inoperative the coating instrumentalities associated with the machine when, for one reason or another, containers

are not present in proper relation to receive coating material therefrom.

A further object of the invention is to provide a single container handling system for both the coating machine and the wax drain oven, thereby avoiding the necessity for transferring the containers from holders associated with the coating machine to independent holders associated with the drain oven conveyor. To this end, the invention provides a single conveyor having can holders pivotally connected thereto, trained for continuous movement through the coating machine and the wax drain oven and to a transfer station at the exit end of the drain oven, where the containers are transferred to the settling oven conveyor.

A further object of the invention is to simplify the delivery of containers to the wax coating machine, and to avoid a transfer of the containers from holders or pockets associated with an infeed device to independent holders in the coating machine. To this end, the invention provides means for delivering the containers to the holders associated with the aforementioned continuous conveyor at an infeed station before the holders enter the coating machine and immediately beyond the aforementioned transfer station.

A further object of the invention is to provide improved coating material projecting assemblies in the coating machine, adapted to cooperate in a novel manner with the containers carried by the holders associated with the conveyor which is trained for movement through the coating machine.

A further object of the invention is to provide a novel arrangement of can feeler mechanism, positioned to cooperate with the containers in the holders associated with the above mentioned conveyor, before the holders enter the coating machine, and to provide means responsive to the feeler mechanism for rendering the coating material projecting assemblies inoperative, before they reach the position to cooperate with empty can holders.

Other and further objects and advantages of the invention will be apparent to those skilled in the art from a consideration of the following description of a specific embodiment of the invention, shown in the accompanying drawings in which:

Figure 1 is a somewhat diagrammatic side elevation of an apparatus in accordance with the invention.

Figure 2 is a plan view of the coating machine and certain of the associated instrumentalities.

Figure 3 is a longitudinal sectional view through the upper portion of the coating machine.

Figure 4 is a similar view through the lower portion of the machine.

Figure 5 is a fragmentary plan view with certain parts broken away, showing the coating machine table and the mechanism for controlling the operations of the coating material projecting assemblies.

Figure 5a (Sheet 7) is a circuit diagram suitable for actuating the mechanism shown in Figure 5.

Figure 6 is a fragmentary horizontal section taken on line 6-6 of Figure 3.

Figure 7 is a similar fragmentary horizontal section taken on line 7-7.

Figure 8 is a similar fragmentary horizontal section taken on line 8-8.

Figure 9 is a transverse section and elevation showing a preferred form of conveyor track hanger and the can holders carried by the conveyor.

Figure 10 is an elevation of a can feeler.

Figure 11 is a top plan view thereof.

Figure 12 is a fragmentary horizontal section and plan view, similar to Figure 5, but showing a modified form of key.

Figure 12a (Sheet 7) is a circuit diagram for actuating the control mechanism shown in Figure 12, and

Figure 13 is a fragmentary view similar to a portion of Figure 3, showing the relation of parts when an empty can holder passes through the machine.

Figure 1 of the drawings shows the general relation of the coating machine to the associated machines in the container coating line. A container preheating oven 10, positioned at a relatively high level has a conveyor consisting of a pair of cables 11 trained therethrough and guided about a pair of sheaves 12 at the delivery end. The cables are passed below guide rollers 13 and then above similar rollers 14, 15 to end sheaves 16, about which they are trained, for return along a run 17, over guide rollers 18 to the wax settling or distributing oven 19, positioned at a lower level below the preheating oven 10 and preferably supported by a common frame 20. Thus it will be apparent that a single conveyor may be employed for the preheating oven and the wax settling oven, with an upper run in the former and a lower return run in the latter.

A twister chute 23 receives the containers from the cables 11 and leads them laterally or forwardly to one side of the conveyor 11 and simultaneously swings them from the vertical, neck-up position to a substantially horizontal position, as indicated at 25.

A vertically disposed dial or star wheel 26, having horizontally positioned peripheral pockets 27 is journaled for rotation on a horizontal shaft 28 at the discharge end of the twister 23, the shaft being supported by a frame 29 carried by posts 30 supported from the floor 31. The containers accumulate in substantially a solid line in the twister 23 and are delivered one-by-one to the pockets in the dial for subsequent transfer to the combined coating machine and drain oven conveyor.

The latter conveyor preferably comprises a chain 35 trained for movement along a horizontal path, about a sprocket 36 associated with the rotatable table 37 of the coating machine and about a sprocket, not shown, at the far end of the wax

drain oven 38. The chain is supported in its travel along this horizontal path by carriages or travelers having rollers engaging suitable tracks, as hereinafter explained. The conveyor has a plurality of can holders 39 pivotally connected thereto for swinging movement through substantially 180° from a position holding the containers in inverted, neck-down relation, to a vertical, upright neck-up position. As the holders 39 move under the dial 26, they are held in horizontal position for the reception of containers from the pockets in the dial. They swing downwardly to the inverted position immediately as they leave the dial and are held in that position during their passage through the coating machine, as they move around through a substantially semi-circular path along the periphery of the table. They emerge from the coating machine on the far side of the table, as viewed in Figure 1, and travel along the back run of the conveyor 35, toward the right into the entrance end 40 of the wax drain oven, being held in inverted relation in the holders during their entire passage through the drain oven.

As the holders and the cans emerge from the exit end 38 of the drain oven, they are swung upwardly to a horizontal position, where they may pass through a neck-wiping apparatus, of the type shown in Patents Nos. 2,295,576 and 2,295,575, dated Sept. 15, 1942.

The holders and the containers therein are then swung from the horizontal position upwardly to a vertical, neck-up position, as they approach the lower run 47 of the cable conveyor leading to the wax settling oven. The holders position the uprighted cans above the run 47 of the cable conveyor and the cans are deposited thereon in upright relation for movement through the wax settling oven.

The devices for clamping the containers in the holders 39 and the cam track means for swinging these holders will be described more particularly as the specification proceeds.

The coating machine proper comprises a base 45 having a laterally offset portion 46 carrying a motor 47 and a speed reduction assembly 48, the sprocket 49 of which is connected by a chain 50 to a sprocket 51 on the motor shaft. A main driving shaft 52 projecting upwardly from the speed reducer 48 carries a pinion 53, in mesh with a pinion 54 on a counter shaft 55, serving as the main driving means for the machine, as hereinafter explained. It will be noted that the countershaft 55 is journaled in bearings 56, 57 carried by the pedestal 60 and that a pinion gear 58 is fast upon its upper end.

The base 45 supports a pedestal casting 60 in which a stationary, vertically disposed column or shaft 61 is mounted. A plurality of struts 62, 63 projecting upwardly and outwardly from the pedestal 60 are connected integrally to an annular platform 64 upon which a steam heating radiator 65 is supported, by bosses 66 projecting upwardly through appropriate openings in an interposed insulation casing 67. The stationary annular platform 64 also carries an upstanding marginal wall 68, spaced outwardly from the heating pipes, for purposes hereinafter described.

The stationary column 61 constitutes a shaft about which the rotatable table 37 of the coating machine is journaled. The table comprises a lower central section or hub 70 supported by a thrust bearing assembly 71 carried by the upper end of the pedestal 60 and by bearing assemblies 72, 73 on the column 61.

The hub portion 70 of the lower section of the table is provided with a plurality of circumferentially arranged vertical bores or sockets 74 which are closed at their lower ends by an annular flange 75 of an internally toothed ring gear 76, bolted to the undersurface of the hub member 70, and in mesh with the pinion 58 on the upper end of the counter shaft 55.

The lower table section further comprises an annular wax reservoir or tank 77, bolted to the ring gear 76 and having annular inner and outer walls 78, 79 and a floor 80. The outer walls of the reservoir carry an outwardly spaced, depending, skirt-like casing 81 adapted to contain insulating material and projecting downwardly into the space between the steam heater 65 and the upwardly projecting casing wall 68 of the stationary base.

The annular wall 78 of the reservoir carries an outwardly projecting cover or shield 83 for the inner portion of the reservoir, which may be made up of a plurality of sections appropriately secured together and supported by pins 84, threaded into radial bores adjacent the upper end of the wall, the shield being provided with openings 85 for the reception of pump actuating rods hereinafter described.

The table 37 further comprises an upper section 86, journaled about the column 61 and supported upon thrust bearing assemblies 87 carried by the upper end of a stationary sleeve 88 keyed to the central section of the column 61. The upper table section 86 has formed therein a plurality of sets of vertical bores, each set comprising three bores 90, 91 and 92, centered on radial lines, as shown in Figures 2 and 3. Each inner bore 90 is aligned with a corresponding bore 74 in the lower table section, and a vertical rod 93, secured therein, serves as a connecting means for the upper and lower table sections, rigidly securing them together for rotation as a unit. Further, a rod or shaft 94, fast in each bore 91, bears firmly against a seat 95 formed in the shield 83 above its line of connection with the inner wall 78 of the reservoir.

Each pair of rods 93, 94 constitute a vertical guiding means for a vertically reciprocable cam following block or frame 96 having vertical bores 97, 98 embracing the rods and a cam following roller 99 disposed in a cam groove 100 formed in the periphery of a cam plate 101, integral with the sleeve 88, fast upon the column 61. Hence, as the table rotates, as hereinafter explained, the cam following blocks or frames 96 are reciprocated vertically on the rods 93, 94, lubricant being supplied by nipples 102, 103, communicating through passages 104, 105 with appropriate chambers in the bores 97, 98.

The upper table section 86 also carries a sectional, annular sprocket plate 108, having a series of teeth 109 for engagement with the conveyor chain 35, hereinafter described. Another sectional ring or plate 110, mounted above the sprocket 108, receives and supports the rollers carried by the carriages or travellers associated with the conveyor chain and can holders, to carry the weight of those elements and to relieve the sprocket 108 therefrom.

The lower table section, and more particularly the bottom 80 of the wax reservoir, carries a plurality of coating material projecting assemblies, one for each set of vertically extending rods and cam following frames 96. Each assembly comprises a pump cylinder 115 having an intake slot 116 in its side wall, immersed in the hot liquid

wax in the reservoir, a piston 117 therein, urged upwardly by a coil compression spring 118, and a conduit member 119 communicating at one end with the cylinder and at the other end with a nozzle pipe 120, bolted thereon. The pipe 120 carries a nipple 121 having a coating material projecting tip 122 at its upper end. Each assembly includes a pump actuator comprising a rod 125, having its lower end resting upon the piston 117 and extending upwardly through the aligned opening 85 in the shield plate 83. The rod extends upwardly through an opening 126 in the cam following frame 96 and has an enlarged upper end 127 disposed in a similarly enlarged bore in a sleeve member 128 disposed in a vertical bore 129 in the cam follower 96 and constituting an enlarged continuation of the bore 126 therein. The head 127 of the rod 125 is normally seated against the bottom of the enlarged bore in the sleeve 128 by means of a relatively heavy coil spring 130 compressed under a transverse pin 131. The upper end of the sleeve 128 is slidably mounted in the bore 92 in the upper table section 86.

It will be apparent from a consideration of the parts so far described that the pump actuator, comprising the rod 125 and the sleeve 128, is received in and embraced by the cam following block 96 for relative sliding movement of the latter with respect to the former. In order that movement may be transmitted from the cam follower to the pump actuator, means are provided for normally connecting them together for movement in unison. As shown most clearly in Figure 5, each cam follower 96 has a keyway 133 cut in its side face, for the reception of a radially slideable key 134, having a relieved portion 135 clearing the guide rods 93, 94 in both positions of the key. The relieved portion 135 clears the sleeve 128 and disconnects the cam follower from the pump actuator when the key is in its radially outermost position, but when the key is moved inwardly, its projecting edge engages an annular groove 136 in the periphery of the sleeve and effectively locks the cam follower to the pump actuator assembly, so that vertically reciprocating movement is imparted from the former to the latter, to reciprocate the piston 117 and project heated wax upwardly through the nozzle tip 122 into the interior of a can positioned thereabove, under the control of the cam groove 100. It will be noted that the keys 134 are maintained in the keyways by engagement of their rear faces with the adjacent side faces of the adjacent cam following blocks or frames, as shown in Figure 5.

In some cases it is desired to effect the connection between the cam following blocks and the pump actuators when the keys are in their radially outermost positions instead of in their inner positions, as shown in Figure 5. This change may be effected by employing a set of keys of the type shown in Figure 12, each comprising a relieved portion 135a for the guide rods 93, 94, and a second, outwardly spaced relieved portion 135b, positioned to be disposed opposite to the groove 136 in the sleeve 128 when the key is in its radially inwardly projected position. An intermediate key section 134a enters the groove 136 when the key is projected outwardly, to effect driving engagement between the cam follower and the pump actuator.

The central cam plate 101 carries an upper, short, supplemental cam surface 138, positioned to be engaged by the inner end faces of the keys 134, so that each key is projected to its outermost

position during each revolution of the table. The cam 138 terminates in a steep, substantially radial shoulder 139 so that each key 134 may be projected inwardly from the radially outermost to the radially innermost position, to engage or disengage the pump actuator, as the case may be, depending upon the type of key employed. As shown in Figure 5, an exteriorly positioned cam surface 140, normally positioned in the path of movement of the ends of the keys 134 serves to project them inwardly to effect the desired connection between the cam followers and the pump actuators. The cam 140 projects from the lower end of a sleeve 141, mounted for oscillation upon a vertical shaft 142, supported from above, as hereinafter explained. At its upper end, the sleeve carries a tail piece 143 having spaced stops 144, 145 embracing a pin 146 to limit the oscillating movement of the sleeve and the cam 140, under the influence of a spring 147 in one direction and a solenoid 148 in the other direction, the armature 149 of the solenoid being connected by links 150 to the tail piece 143. So long as the armature is energized, in this arrangement, the cam 140 is projected outwardly against the action of the spring 147 in the path of movement of the keys 134 so that the keys are moved inwardly to operative position as they pass the cam. When the solenoid is deenergized, however, the spring 147 retracts the cam 140, so that the keys 134 are left in their outwardly projected, inoperative position, to which they were moved by the stationary, central cam 138.

If keys of the type shown in Figure 12 are employed, the cam 140 will be normally in the retracted position and the solenoid normally deenergized, to the end that the keys will remain in their outwardly projected, operative position. When the solenoid is energized, however, the movable cam 140 will be projected into the path of movement of the keys 134, thereby moving them inwardly to the inoperative position.

After describing a preferred mechanism for supporting and conveying the line of cans, the device for controlling the operation of the solenoid 148 and the movable cam 140 will be referred to.

As shown in Figures 2, 3 and 9, the central column 61 of the machine carries a cap 155, clamped thereto and serving as a support for a laterally extending channel member 156, secured at its other end to the drain oven or the supporting framework therefor, not shown. As a point adjacent the periphery of the upper section of the rotatable table, the channel member 156 carries a yoke or hanger 157 having a pair of depending arms 158, 159 formed integrally therewith and serving as supporting means for longitudinally extending tracks members 160, 161, in the form of channel sections, disposed in parallel relation and leading to and from the table of the coating machine, substantially tangentially with respect thereto. These channel members extend from the periphery of the table to the ends of the wax drain oven, where they are supported in any appropriate manner by the framework thereof.

As best shown in Figure 9, the upper flanges of the channel members 160, 161 carry track rods 162, welded or otherwise secured thereto, while the lower flanges support horizontal plates 163 and strips 164, 165, defining a downwardly facing guide channel 166. The vertical webs of the channel members 160, 161 similarly carry out-

wardly facing strips 167, constituting track surfaces as hereinafter explained.

The forwardly projecting arm of the hanger 157 supports a pair of upwardly projecting guide plates 168, 169, defining a channel for the run 17 of the cable conveyor leading to the wax settling oven.

The outer ends of the hanger also carry depending brackets 170, 171 which support a strip 172, extending along a curved path around the periphery of the upper section of the wax coating machine in position to prevent inadvertent outward swinging movement of the pivoted can holders 39 under the influence of centrifugal force.

Alternate links of the conveyor chain 36 carry a pair of upwardly and downwardly projecting wings 175, to which travellers or carriages 176 are secured, each carriage having a pair of supporting rollers 177 journaled on inclined axes at its upper end, riding along the track rods 162. Vertically disposed rollers 178 carried by the chain pintles, are positioned to engage the guide strips 167 and prevent tipping of the carriages relative to the tracks.

The can holders 39 comprise cradle members 180, pivoted to the carriages at 181 for swinging movement in a vertical plane from an inverted, neck-down position, to an upright, neck-up position. Each cradle has a seat 182 for the bottom edge of the side wall of a container 200 and for the double-seam 201 thereof, and a pair of wings 183 for engaging the side wall adjacent the upper end. A clamping yoke member 184, pivoted to the cradle at 185, has a bifurcated end 186 shaped to engage the conical end 203 of the container, to urge the same against the seat 182 under the influence of a tension spring 187. The opposite end of each clamp member 184 carries a roller 188, adapted to engage a cam rail, to swing the clamp against the action of the spring 187 to release the container at a predetermined time.

Each pivoted cradle member 180 also has a laterally projecting arm 189, carrying a roller 190, disposed in the channel 166 between the downwardly projecting guide strips 164, 165, to maintain the can holder in predetermined position relative to the carriage 176. This roller 190 engages a cam rail 191 at predetermined times to swing the cradle from the neck/down position, upwardly to a horizontal position and then to the vertical, neck-up position for transfer of the container to the conveyor leading to the wax settling oven.

Reference is made to the copending application of Gladfelter and Ehrlich, Serial No. 405,866, filed August 7, 1941, for a complete description of a similar, though specifically different, can holder assembly.

The depending bracket 170 carried by the forwardly projecting arm of the hanger 157 has secured thereto a rearwardly projecting angle iron 205 carrying the can feeler mechanism, which controls the operation of the solenoid 148. As shown in Figures 10 and 11, a downwardly projecting bolt 206, supported by the upper flange of the angle iron 205, carries a pivoted lever 207, having a feeler plate 208 adjustably secured thereto by screws 209 disposed in slots 210, so that the plate may be longitudinally adjusted through predetermined limits. The lever 207 carries an upwardly projecting finger 211, adapted to engage a button 212 of a micro switch 213, mounted upon the horizontal flange of the angle iron 205.

The finger 211 is normally held out of contact

with the button 212 by cans 200 in the holders associated with the conveyor chain leading to the coating machine, but when an empty holder is presented, a tension spring 214, connected between the finger and the switch casing 213, swings the feeler plate 208, the lever 207 and the finger 211 inwardly into contact with the button 212, thereby either opening or closing the circuit leading to the solenoid 148, depending upon whether a normally closed micro switch and circuit, as shown in Figure 5a, are employed, or a normally open micro switch and circuit, as shown in Figure 12a, which, in turn, depends upon the use of locking keys of the types shown in Figure 5 or Figure 12. In any event, when the switch 213 is actuated by an empty holder passing the feeler plate 208, the movable cam 140 is shifted by the solenoid or by the spring 147 to a position such that the key associated with the corresponding coating material projecting assembly is projected to, or remains in, the inoperative position, to the end that, when that particular assembly joins the empty can holder, the cam following block or frame 96 associated therewith is free to reciprocate vertically, without transmitting corresponding movement to the pump actuating rod 125 and the piston 117, as shown in Figure 13.

The table of the coating machine is driven at predetermined speed by the speed reducer 48, acting through gears 53, 54, shaft 55 and pinion 58, in mesh with the large, internal ring gear 76. The conveyor 11, trained through the preheating oven 10 and the wax settling oven 19, is driven by independent means at a speed correlated with the speed of movement of the wax coating machine table and the conveyor 35, driven thereby. It is important that the infeed dial 26, which receives the containers from the chute or twister 23 and delivers the same to the holders associated with the chain 35 be rotated in properly timed relation with respect to the chain so that a container is delivered from each pocket in the dial to a corresponding holder on the chain. In other words, the dial pockets must register with the can holders on the chain as the holders pass beneath the dial.

Referring to Figures 1, 2 and 4, it will be noted that the counter-shaft 55 carries a sprocket 220 connected by a chain 221 to another sprocket 222 fast on a vertical shaft 223, geared to the horizontal shaft 28 by bevel gears, not shown, in a casing 224 carried by a bracket 225, mounted on the upper ends of the supporting rods 30. Hence, the dial 26, fast on the shaft 28, is driven at a peripheral speed corresponding to the speed of movement of the conveyor chain 35.

It is thought that the operation of the apparatus described above will be apparent from a consideration of this specification. A line of containers, such as the beer cans 200, are carried through the preheating oven 10 in upright relation and emerged therefrom on the upper run of the conveyor 11. The conveyor drops downwardly below the lower rails of the twister 23, leaving the containers supported thereon. The containers move down the twister under the influence of gravity and are tipped forwardly, as viewed in Figure 1, from an upright position to a horizontal position adjacent the lower end thereof. They are picked up, one by one, by the pockets 27 in the vertical dial 26 and are delivered therefrom in horizontal relation to the holders 39 associated with the conveyor chain 35, as the holders pass beneath the dial in horizontal position, the movements of the dial and the con-

veyor chain 35 being timed so that the holders and pockets register below the dial.

The holders swing downwardly to the vertical, inverted position as they leave the dial and, in the latter position, pass the feeler 208. So long as the feeler engages the cans, the switch 213 remains closed and the solenoid 148 is energized, thereby maintaining the movable cam 140 in the path of movement of the keys 134 and projecting the latter inwardly to the operative position, connecting the cam following blocks 96 with the pump actuating rods 93. Hence, as the cans pass around the machine in the holders 39, a stream of wax is projected upwardly through the nozzle tips 122 into the interiors of the cans. A major portion of the excess wax drains back into the reservoir, while the remainder, except for the desired thin coating, drains therefrom as the containers pass in inverted position through the wax drain oven.

If one or more holders fail to receive cans from the dial 26, so that they are empty as they pass the feeler 208, the latter is moved inwardly under the influence of the spring 214, thereby contacting the button 212 and opening the switch 213, which, in this arrangement is a normally closed switch, as indicated in Figure 5a. The solenoid 148 is immediately deenergized and the movable cam 140 is shifted by the spring 147, out of the path of movement of the keys 134, so that the keys are left in their outwardly projected, inoperative position. The feeler and the movable cam are so positioned that they operate upon corresponding can holders and coating material projecting assemblies. That is to say, the holder disposed opposite the feeler at any particular instant will ultimately be combined in the machine with the projecting assembly which at that instant is disposed opposite the cam 140. Hence, the coating material projecting assembly corresponding to an empty holder will be rendered inoperative by the disconnection of the cam following block 96 from the pump actuating rod 125, and coating material will not be projected upwardly when the holder thereabove is empty.

If a key of the type shown in Figure 12 is employed, the movable cam 140 is normally maintained in the retracted position, out of the path of movement of the keys. However, when an empty holder is presented to the feeler 208, the normally open switch, used in this arrangement, as shown in Figure 12a, will be closed, thereby energizing the solenoid and swinging the cam 140 into the path of movement of the keys, to project the same inwardly to the inoperative position.

As the coated containers emerge from the exit end 38 of the drain oven, they are swung upwardly to a horizontal position so that their neck ends may be wiped, as explained above, and, thereafter, they are swung upwardly and rearwardly, as viewed in Figure 1, to a position overlying the run 17 of the conveyor leading to and trained through the wax settling oven 19. The pivoted clamping yokes 184 are swung upwardly by a cam rail engaging the rollers 188, thereby releasing the cans from the holders and permitting the same to be carried away by the cable conveyor.

The containers pass through the wax settling oven in upright, neck-up position, where they are maintained at an elevated temperature, to permit the wax coating to distribute itself over the walls of the containers and more particularly to accumulate along the line of junction between

the side walls and the bottom end members, to seal the double seam.

Although the invention has been described with considerable particularity by reference to the embodiments disclosed in the accompanying drawings, it must be understood that it is not limited to the details of construction shown and described, but covers all modifications coming within the scope of the appended claims and their equivalents.

We claim:

1. A machine for coating the interiors of cans with a liquid coating material comprising a rotatable table, means associated with said table for supporting a plurality of cans in neck-down relation in predetermined position, a nozzle below each can in alignment therewith, a pump connected to each nozzle, a pump actuating member carried by the table for each pump, cam means for operating said member upon rotation of the table, and means for rendering the member inoperative when no can is present in the associated holder.

2. A machine for coating the interiors of cans with a liquid coating material, comprising a rotatable table, a plurality of holders associated therewith adapted to support cans in inverted, neck-down position, a plurality of upwardly directed coating material nozzles below the cans, a pump associated with each nozzle and including a relatively stationary cylinder and a vertically movable piston, a piston actuating rod for each piston, a vertically reciprocable member adjacent each rod carried by the table, cam means for reciprocating the member as the table rotates, and means for establishing operative connection between the member and the rod when a container is present in the associated bracket.

3. A machine in accordance with claim 2 characterized by the inclusion of means for shifting said connecting means to an inoperative position in the absence of a can in the associated bracket.

4. A can coating machine comprising a rotatable table, vertically fixed can holding means associated therewith for supporting a plurality of cans at a fixed elevation with respect to the table in neck-down position, a plurality of coating material projecting assemblies carried by the table, a stationary cam for actuating said assemblies as the table rotates, and means for controlling the operation of said assemblies, each assembly comprising a nozzle fixed with respect to the table, a pump connected thereto, a pump actuating rod, a reciprocable cam following member operatively associated with said cam, and movable connecting means for establishing a driving connection between the member and the rod in one position and for breaking said connection in another position, said controlling means comprising a shiftable cam for controlling the position of said movable connecting means, depending upon the presence or absence of cans in the can holding means.

5. A can coating machine comprising a rotatable table, vertically fixed can holding means associated therewith for supporting a plurality of cans at a fixed elevation with respect to the table in neck-down position, a plurality of coating material projecting assemblies carried by the table, a stationary cam for actuating the assemblies as the table rotates, and means for controlling the operation of said assemblies, each assembly comprising a relatively fixed, upwardly projecting nozzle aligned with the can in the associated holder, a pump connected to and positioned laterally with respect to the nozzle, an upwardly extending

5 pump actuator rod, a reciprocable cam following member operatively associated with said cam and having a vertical bore embracing the actuator, and movable connecting means carried by the member for establishing a driving connection between the member and the actuator in one position and for breaking said connection in another position, said controlling means comprising means actuated by the presence or absence of cans in 10 the holding means for shifting the position of said connecting means.

6. A can coating machine comprising a rotatable table, vertically fixed can holding means associated therewith for supporting a plurality of cans in neck-down position, a plurality of coating material projecting assemblies carried by the table, a stationary cam for actuating the assemblies as the table rotates, and means for controlling the operation of said assemblies, each assembly 15 comprising a relatively fixed nozzle, a pump connected thereto, a vertically extending pump actuator, a vertically reciprocable cam following member operatively associated with said cam and slidably embracing the actuator, and a key carried by the member for establishing driving connection with the actuator in one position and for disconnecting the same in another position, said controlling means comprising means for shifting the positions of the keys, depending upon the presence or absence of cans in the holding means.

7. A can coating machine comprising a rotatable table, can holding means thereon for supporting a plurality of cans in vertically fixed, neck-down position, a plurality of coating material projecting assemblies carried by the table and means for controlling the operation of said assemblies, each assembly comprising a relatively fixed nozzle, a pump connected thereto, a vertically extending pump actuator having a transverse key-way therein, a vertically reciprocable member slidably embracing the actuator and a movable key carried by the member having a portion adapted to enter said key-way to establish driving connection with the actuator in one position and having a relieved portion adapted in another position of the key to disconnect the member from the actuator, said controlling means comprising means for shifting the positions of the keys, depending upon the presence or absence 50 of cans in the holding means.

8. A can coating machine comprising a rotatable table, can holding means thereon for supporting a plurality of cans in vertically fixed, neck-down position, a plurality of coating material projecting assemblies carried by the table and means for controlling the operation of said assemblies, each assembly comprising a relatively fixed nozzle, a pump connected thereto, a vertically reciprocable member slidably embracing the actuator and a key carried by the member for radial sliding movement between inner and outer positions, said key having a portion adapted to enter the key-way in one position to establish driving connection with the actuator and in the other position to disconnect the same, said controlling means comprising means for shifting the radial positions of the keys depending upon the presence or absence of the cans in the holding means.

65 9. A can coating machine comprising a rotatable table, can holding means thereon for supporting a plurality of cans in neck-down position, a plurality of coating material projecting assemblies carried by the table, a stationary cam for

70 75

actuating the assemblies as the table rotates, and means for controlling the operation of said assemblies, each assembly comprising a relatively fixed, upwardly projecting nozzle, a pump connected thereto, a vertically extending pump actuator, a vertically reciprocable cam following member operatively associated with said cam and slidably surrounding said actuator, and a radially moving key carried by the member for establishing driving connection with said actuator in one position and for breaking said connection in another position, said controlling means comprising a second stationary cam adapted to project each of said keys to one position during each revolution of the table, a movable cam adapted in one of its positions to leave the keys as projected by the last-mentioned stationary cam and in its other position to project the keys to their other position, and means controlled by the absence of a can in a can holder for shifting the movable can.

10. A can coating machine comprising a stationary, substantially vertical column, a table journaled for rotation thereon and comprising a lower section having a reservoir therein and an upper section having a plurality of can holders supported thereon, means spaced outwardly from said column connecting the upper and lower sections for movement in unison, a stationary cam on the column opposite said means, a plurality of vertically movable cam following frames slidably mounted on said means and engaging said stationary cam, a plurality of coating pumps and nozzles communicating with the reservoir and carried by the lower section, and means for actuating the pumps, each of said means comprising an actuator slidably disposed in the associated frame, and means for operatively connecting the frame to the actuator, whereby movement is transmitted thereto.

11. A can coating machine comprising a stationary, substantially vertical column, a table journaled for rotation thereon and comprising a lower section having a reservoir therein and an upper section having a plurality of can holders supported thereon, means spaced outwardly from said column connecting the upper and lower sections for movement in unison, a stationary cam on the column opposite said means, a plurality of vertical movable cam following frames slidably mounted on said means and engaging said stationary cam, a plurality of coating pumps and nozzles communicating with the reservoir and carried by the lower section, and means for actuating the pumps, each of said means comprising an actuator slidably disposed in the associated frame, means for operatively connecting the frame to the actuator, whereby movement is transmitted thereto, and means for disconnecting the frame from the actuator in the absence of a can in the associated holder, whereby movement is not transmitted from the frame to the pump actuator when no can is in position to receive coating material from the pump and the nozzle.

12. A can coating machine comprising a stationary, substantially vertical column, a table journaled for rotation thereon and comprising a lower section having a reservoir therein and an upper section having a plurality of can holders supported thereon and restrained against relative vertical movement with respect thereto, a plurality of pairs of rods spaced outwardly from said column and connecting the upper and lower sections for movement in unison, a stationary cam on the column opposite said rods, a plurality

of vertically movable cam following frames slidably mounted on said pairs of rods and engaging said stationary cam, a plurality of coating pumps and nozzles aligned with the can holders and carried by the lower section, and means for actuating the pumps, each of said means comprising a pump actuating rod slidably disposed in the associated cam following frame, means for operatively connecting the frame to the actuating rod, whereby movement is transmitted thereto, and means for disconnecting the frame from the actuating rod in the absence of a cam in the associated holder, whereby movement is not transmitted from the frame to the rod when no can is in position to receive coating material from the pump and the nozzle.

13. A machine for coating the interiors of cans with a liquid coating material, comprising a rotatable table, a plurality of can holders movable with the table in vertically fixed position thereon for supporting the cans in inverted relation, a plurality of upwardly projecting nozzles carried by the table, fixed with respect thereto and terminating immediately below the lower ends of the cans in the holders, an independent pump communicating with each nozzle, a vertically reciprocating member associated with each pump, means for connecting the member to the pump to actuate the latter when a can is present in the associated holder, and means for disconnecting the pump from the member in the absence of a can in the holder.

14. In combination, a machine for coating the interiors of cans with wax, an endless chain having a plurality of can holders thereon trained for movement through said machine and through a path remote therefrom, and control means for the coating machine, said machine comprising a plurality of coating material projecting assemblies movable with the can holders on the chain and aligned therewith as the holders travel through the machine, said control means comprising a can feeler disposed adjacent the chain at a point spaced from the coating machine, means for displacing the feeler when an empty can holder on the chain is presented thereto, and means actuated by the displacement of the feeler for rendering inoperative the coating material projecting assembly which subsequently is aligned and travels with the empty holder.

15. An apparatus for coating the interiors of cans comprising a rotatable table, a conveyor having an infeed run leading toward the table and a peripheral run trained about a portion of the table, a plurality of can holders carried by the conveyor, a plurality of coating material projecting assemblies carried by the table for movement along a circular path in position to cooperate with the holders to coat the interiors of the cans while the holders and the cans travel through said peripheral run, means adjacent the circular path of movement of the associated assemblies but positioned in advance of the peripheral run of the holders for selectively rendering the assemblies inoperative, a can feeler disposed adjacent the infeed run of the conveyor, means for displacing the feeler when an empty holder is presented thereto and means actuated by the displacement of the feeler for actuating the first-mentioned means to render inoperative the corresponding assembly, before the same enters said peripheral run in cooperative relation to the empty holder.

16. An apparatus for coating the interiors of cans, comprising a rotatable table, substantially

parallel tracks leading toward and from the table, a conveyor supported by said tracks and trained about the table, a plurality of can holders carried by the conveyor, a plurality of coating material projecting assemblies on the table in position to cooperate with the holders and to coat the interiors of cans held thereby, means positioned adjacent the table between the tracks, for selectively rendering the assemblies inoperative, a can feeler disposed adjacent the track leading toward the table, means for displacing the feeler when an empty can holder approaching the table is presented thereto, and means actuated by the displacement of the feeler for actuating the first-mentioned means, to render inoperative the assembly which is subsequently positioned in cooperative relation with the empty holder.

17. An apparatus for coating the interiors of cans, comprising a rotatable table, a pair of spaced apart substantially parallel tracks leading toward and from the table, supporting means for the ends of the tracks adjacent the table, a conveyor trained for movement along said tracks and along a peripheral path around the opposite side of the table, a plurality of can holders carried by the conveyor, a plurality of coating material projecting assemblies carried by the table in position to cooperate with the holders as the latter move along said peripheral path, means carried by said track supporting means adjacent

the table and ahead of said peripheral path for selectively rendering the assemblies inoperative, a can feeler adjacent the track leading toward the table and positioned ahead of the table, means for displacing the feeler when an empty can holder is approaching the table, and means actuated by the displacement of the feeler for actuating the first-mentioned means to render inoperative the assembly which is subsequently positioned in cooperative relation with the empty holder.

18. Apparatus in accordance with claim 15, characterized in that the feeler controls an electrical circuit which is connected to operate the means for selectively rendering the coating material projecting assemblies inoperative.

19. Apparatus in accordance with claim 15, characterized in that the feeler comprises an electric switch normally held closed by a series of cans in the holders and means for opening the switch when an empty holder is presented, and in that the means for rendering the coating material assemblies inoperative comprises a movable cam, a solenoid energized by said switch for projecting the cam into an inoperative position and a spring for projecting said cam into a position to operate said means when the solenoid is deenergized.
